RAILWAY TRAFFIC CONTROLLING APPARATUS

Filed Jan. 21, 1929

UNITED STATES PATENT OFFICE

EUGENE A. LOWMAN, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY TRAFFIC CONTROLLING APPARATUS

Application filed January 21, 1929. Serial No. 333,867.

My invention relates to railway traffic controlling apparatus, and particularly to apparatus of the type comprising train carried governing means controlled by energy received from the trackway. More particularly my present invention relates to the trackway portion of such apparatus.

I will describe one form of trackway apparatus embodying my invention, and will then point out the novel features thereof in claims.

The accompanying drawing is a diagrammatic view illustrating one form of trackway apparatus embodying my invention.

Referring to the drawing, the reference characters 1 and 1^a designate the track rails of a stretch of railway track over which traffic normally moves in the direction indicated by the arrow. These rails are divided, by means of insulated joints 2, into a plurality of successive blocks A—B, B—C, etc., each of which contains a plurality of sections. For example, block A—B contains two sections A—X and X—B, and block B—C contains two sections B—Y and Y—C. Track circuit current is constantly supplied to each section by a track battery 3 connected across the rails adjacent one end of the section. Each section is also provided with a track relay, designated by the reference character R with a distinguishing exponent, and connected across the rails adjacent the opposite end of the section.

Means are also provided for at times supplying each section with alternating train controlling current from a point adjacent the exit end of the section. For this purpose each section is provided with a track transformer designated by the reference character T with an exponent corresponding to the location and having its secondary connected across the rails adjacent the exit end of the corresponding section.

Under some conditions of operation it is desirable to operate apparatus of the type here described in localities where a uniform and reliable source of alternating current is not available. I therefore propose to provide each block with a source of direct current, such for example, as a line battery, each of

reference character H with an exponent corresponding to the location, and to operate by means of current from this battery apparatus which will supply alternating current to the trackway. The batteries H may be storage batteries, and each of these batteries may be trickle-charged from a transmission line 4, 4^a, which may be supplied with energy from a suitable source, such as an alternator Q. Each line battery receives energy from the transmission line through a transformer and a rectifier, designated by the reference characters L and P respectively, with suitable distinguishing exponents. With this arrangement the operation of the apparatus receiving energy from the batteries H is not subject to interruption as a result of failure of the supply of energy from the transmission line.

Each block is provided with an approach relay, designated by the reference character D with a distinguishing exponent, and located adjacent the exit end of the block. Each block is also provided with an auxiliary relay, designated by the reference character G with an exponent corresponding to the location, and disposed adjacent the entrance end of the block. Referring particularly to block A—B, the auxiliary relay G^A and the approach relay D^B for this block are normally connected in series over a circuit which may be traced from battery H^B, through wires 11 and 12, winding of relay D^B, wire 13, front contact 14 of relay R^B, wire 15, front contact 16 of relay R^B, wire 17, winding of relay G^A, and wires 18, 19, 20, 21, 22, 23, 24, 25 and 26, back to battery H^B. The parts are so proportioned, however, that when this circuit is closed, relay G^A is energized, but relay D^B does not then receive enough current to close its front contacts. If a train occupies section A—X, however, track relay R² is de-energized, so that wire 15 in the circuit just traced is disconnected from wire 17 and is connected through back contact 16 of relay R², wire 27, resistor 28 and wires 29 and 30, wire 19, and thence as before back to battery H^B. It will be plain, therefore, that when relay R² is de-energized, relay G^A is replaced by resistor 28 in the circuit for relay D^B. The

resistor 28 is so proportioned that when relay R² is de-energized the current then supplied to relay D^B is sufficient to close the front contacts of relay D^B. Still another circuit may be traced for relay D^B from battery H^B, through wires 11 and 12, winding of relay D^B, wire 13, back contact 14 of relay R³, resistor 31, and wires 32, 33, 34 and 26, back to battery H^B. The resistor 31 is so proportioned that when the circuit just traced is closed, relay D^B is energized to close its front contacts. It will be plain from the foregoing that when block A—B is unoccupied, so that relays R² and R³ are both energized, relays 15 G^A and D^B are supplied in series with current which closes relay G^A but does not close relay D^B. When either of sections A—X or X—B is occupied by a train, however, relay G^A is de-energized, but the current then supplied to relay D^B is sufficient to close this relay.

Each block is provided with a coding device, designated by the reference character K with a suitable exponent, and operating at times upon current received from the associated battery H to supply periodically interrupted alternating current to the trackway. Referring particularly to device K^B, this device comprises a direct current motor 7 which is provided with a circuit passing from battery H^B, through wires 11 and 35, front contact 36 of relay D^B, wire 37, motor 7 of device K^B, and wires 38, 34 and 26, back to battery H^B. It will be plain that the motor 7 is normally de-energized, but that when relay D^B becomes energized, as by the entrance of a train into block A—B, motor 7 is connected with battery H^B, so that the motor is then operated. Operatively connected with the motor 7 is an alternating current generator 8 and two code wheels 9^a and 10^a, which operate contacts 9 and 10, respectively, in such manner that when motor 7 is running, the contacts 9 and 10 are periodically opened and closed at different frequencies. The alternating current delivered by generator 8 of coding device K^B is supplied, over contact 9 or contact 10, depending upon the condition of relay G^B, to the primary 6 of transformer T^X or to the primary 6 of transformer T^B, depending upon the condition of relay R³.

As shown in the drawing, relays G^B and R³ are both energized, and if, under these conditions relay D^B becomes energized so that motor 7 of device K^B is operated, the alternating current delivered by generator 8 flows over wires 39 and 40, contact 10 of coding device K^B, wire 41, front contact 42 of relay G^B, wire 43, front contact 44 of relay R³, wire 45, primary 6 of transformer T^X and wires 46, 23, 24, 25, 34 and 38 back to generator 8. Under these conditions, therefore, alternating current supplied by generator 8 is periodically interrupted by contact 10 and supplied to the rails of section A—X. If relay R³ is de-energized, the

circuit just traced is interrupted and current is then supplied from generator 8 over the circuit previously traced as far as wire 43, and thence through back contact 44 of relay R³, wire 47, primary 6 of transformer T^B, and wires 48, 49, 32, 33 and 38 back to generator 8. Under these conditions, then, the current supplied by generator 8 is periodically interrupted by contact 10 and is supplied to the rails of section X—B. It should be noted that if relay G^B is de-energized, so that back contact 42 of this relay is closed, the circuit for generator 8 will then include contact 9 of device K^B instead of contact 10, and the current supplied to the track rails will be interrupted at a different frequency.

Before describing the operation of the apparatus as a whole, it should be pointed out that the trackway apparatus herein shown and described is intended for cooperation with train carried governing means which is responsive to the frequency of the periodic interruptions in the alternating train controlling current supplied to the trackway. For example, the train carried governing means may display a proceed indication when the rails occupied by the train are supplied with alternating current which is periodically interrupted at the frequency of operation of contacts 10 of the coding devices K, and may display a caution indication when the rails are supplied with alternating train controlling current interrupted at the frequency of operation of contacts 9 of the coding devices K. If the supply of alternating train controlling current is interrupted, a stop indication is received on board the train.

As shown in the drawing, the stretch of track is unoccupied, so that all track relays R are energized. Each auxiliary relay G is therefore energized and each approach relay D is open, so that all of the coding devices K are at rest. I will now assume that a train, moving in the direction indicated by the arrow passes through the stretch of track shown in the drawing. When the train enters section A—X relay R² becomes de-energized, thereby replacing relay G^A by resistor 28 in the circuit for relay D^B. Relay G^A therefore becomes de-energized and relay D^B picks up. As a result, current from battery H^B operates motor 7 of coding device K^B to drive the generator 8 and the code wheels 9^a and 10^a. Since relays R³ and G^B are now energized, alternating current, periodically interrupted by contact 10, is supplied to the primary of transformer T^X so that a proceed indication is received on board the train. When the train enters section X—B, relay R³ becomes de-energized, thereby transferring the circuit for relay D^B to include resistor 31 and back contact 14 of relay R³. Relay D^B therefore remains energized

and the coding device K^p continues to operate. Since relay R^3 is now de-energized however, the supply of current to transformer T^x is interrupted at front contact 44 of this relay, but transformer T^p is supplied with train controlling current over contact 10 of device K^p through back contact 44 of relay R^3 . The train therefore continues to receive a proceed indication as it moves through section X-B. When the rear of the train passes out of section A-X, relay R^2 becomes energized, but relay G^A remains open because its circuit is now open at front contact 14 of relay R^3 . When the train enters section B-Y, relay G^p becomes de-energized, and relay D^c picks up, thereby setting coding device K^c into operation and supplying train controlling current to the rails of block B-C in the same manner as already described in connection with block A-B. When the rear of the train passes out of section X-B, the energization of relay R^3 completes the normal series circuit for relays G^A and D^p , so that relay G^A closes and relay D^p opens. The coding device K^p is then de-energized, and the supply of train controlling current to block A-B is discontinued. The operation of the apparatus as the train passes through block B-C will be understood from the drawing without further explanation.

It will be manifest from the foregoing that if any portion of block B-C is occupied by a train, relay G^p will be de-energized. If a train enters section A-X under these conditions, the operation of the apparatus will be the same as was described hereinbefore except that contact 9 of device K^p is now included in the circuit for generator 8 of device K^p , so that the current supplied to the rails is interrupted at the frequency of operation of contact 9. Under these conditions the train receives a caution indication, and this indication will, of course, persist as the train proceeds through section X-B.

Furthermore, if a train occupies a forward section in a block, such for example as Y-C or B-C, and a following train enters the block, the following train will not receive train controlling current, so that a stop indication will be received on board the train.

One advantage of my invention is that I have provided apparatus operating upon direct current which may be supplied from a storage battery and which delivers periodically interrupted alternating current to the track rails for the control of train carried governing means. It is therefore unnecessary to depend upon a transmission line for the integrity of the apparatus at each location. With apparatus embodying my invention, if the supply of current to the transmission line 4, 4^a, should be interrupted, the batteries H^p would be unaffected and would continue to

supply energy to the trackway apparatus for a considerable interval of time. As a result, the train controlling apparatus would suffer no interference whatever.

The broad combination of a direct current motor driving an alternating current generator and also driving a contact for coding the alternating current supplied to the rails, is not claimed herein but this combination forms the subject-matter of a copending application, Serial No. 245,377, filed January 9, 1928, by E. C. Sasnett, for automatic train control systems.

Although I have herein shown and described only one form of trackway apparatus embodying my invention, it is understood that various changes and modifications may be made therein within the scope of the appended claims without departing from the spirit and scope of my invention.

Having thus described my invention, what I claim is:

1. In combination, a stretch of railway track, a transformer having its secondary connected with the rails of said stretch, a source of direct current and means receiving energy from said source for supplying periodically interrupted alternating current to the primary of said transformer.

2. In combination, a stretch of railway track, a transformer having its secondary connected with the rails of said stretch, a source of direct current, means receiving energy from said source for supplying alternating current to the primary of said transformer, and means for at times periodically interrupting said alternating current at different frequencies depending upon traffic conditions.

3. In combination, a forward and a rear section of railway track, a track relay for each said section, an auxiliary relay, an approach relay, a circuit including said auxiliary relay and said approach relay and front contacts of both said track relays, a second circuit for said approach relay including a front contact of the track relay for said forward section and a back contact of the track relay for the rear section, a third circuit for said approach relay including a back contact of the track relay for the forward section, said approach relay being closed when said second or third circuit is closed but not when said first circuit is closed, means controlled by said approach relay for governing the supply of train controlling current to said forward and rear sections, and means controlled by said auxiliary relay for supplying train controlling current to the rails in rear of said rear section.

4. In combination, a forward and a rear block of railway track, an auxiliary relay for controlling the supply of train controlling current to said rear block, an approach relay for controlling the supply of train control-

ling current to said forward block, means for normally supplying current of one value to said auxiliary relay and said approach relay in series to close said auxiliary relay but not said approach relay, and means for supplying current of a different value to said approach relay but not to said auxiliary relay when said forward block is occupied by a train.

5. In combination, a plurality of successive blocks of railway track, an auxiliary relay and an approach relay for each section, means for normally supplying current of one value to the auxiliary relay and approach relay for each block in series, to close such auxiliary relay but not such approach relay, means effective when a block is occupied for supplying current of a different value to the associated approach relay, apparatus for each block controlled by the associated approach 15 relay for generating alternating current, two contacts for each section periodically operated at different frequencies, and means for supplying current from each said apparatus to the corresponding block over one or the 20 other of the associated contacts depending upon the condition of the auxiliary relay for the block next in advance.

6. In combination, a forward and a rear section of railway track, a track relay for 30 each section, an auxiliary relay, an approach relay, a circuit including said auxiliary and approach relays and a front contact of each said track relay, and effective to close said auxiliary relay but not said approach relay, 35 two resistors each having a lower resistance than said auxiliary relay; a second circuit including said approach relay, one of said resistors, a front contact of the track relay for the forward section, and a back contact of the track relay for the rear section; a third circuit for said approach relay including the other resistor and a back contact of the track relay for the forward section, means controlled by said approach relay for governing 40 the supply of train controlling current to both said sections, and means controlled by said auxiliary relay for governing the supply of train controlling current to the track in rear of said rear section.

50 In testimony whereof I affix my signature.
EUGENE A. LOWMAN.
